Farabow, Garrett & Dunner LLP(57) **CLAIM**

The ornamental design for a perfume tester container, as shown and described.

DESCRIPTION

FIG. 1 is a front top left perspective view of a perfume tester container showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a left side view thereof;

FIG. 7 is a right side view thereof; and,

FIG. 8 is a front top left perspective view thereof showing an unclaimed key in a condition of use.

The broken lines in the drawings represent environmental subject matter specifically a key in FIG. 8, and form no part of the claimed design.
